Atty.

UNITED STATES PATENT OFFICE.

MICHEL MICHELS, OF CHICAGO, ILLINOIS.

FEED-TROUGH ATTACHMENT.

SPECIFICATION forming part of Letters Patent No. 415,392, dated November 19, 1889.

Application filed July 23, 1889. Serial No. 318,468. (No model.)

To all whom it may concern:

Be it known that I, MICHEL MICHELS, a citizen of the United States of America, residing at Chicago, in the county of Cook and State 5 of Illinois, have invented certain new and useful Improvements in Feed-Trough Attachments to Wagon-Poles, of which the following is a specification, reference being had therein to the accompanying drawings.

10 This invention has for its object to provide a feed-trough to be attached to the end of a wagon-tongue for feeding horses therefrom without unhitching them, and which, when not in use, can be folded in a small compass 15 for placing it under the wagon-seat; and with these objects in view my invention consists of the novel devices and combinations of devices hereinafter described and specifically claimed.

In the accompanying drawings, Figure is a 20 perspective view, and Fig. 2 an elevation, of the feed-trough as it appears when attached to a wagon-tongue; Fig. 3, a view of the same as folded, and Fig. 4 a section showing the connection of the ends of the feed-trough 25 with the spreader-arms.

Corresponding letters in the several figures of the drawings designate like parts.

A and B denote two S-shaped arms, each provided at one end with a segmental jaw a. 30 Just above these jaws a the arm A has rigidly secured two-prong plates b, the eyed ends of which engage the arm B, being pivotally and detachably coupled therewith by a pin c. Above prong-plates b is pivoted to arm A a lever d, provided with ratchet-teeth that engage a hook e, rigid with arm B, and to this lever is coupled the pin c by a chain f. The two segmental jaws a will be placed over the end of the wagon-tongue M, one against each 40 side, and then, after clamping the wagon-tongue between, by pulling the arms A and B downward, and thereby forcing the jaws a toward each other, the lever d is swung down for one of its teeth to engage the hook e and 45 lock the arms A and B upon the wagon-pole, so as to be rigid therewith.

The upper and outer ends of the arms A and B are tapering, each with a head g, and just under said head g these ends are round, 50 while a little below they are squared for coupling and holding the end sticks h, passed

through the hemmed ends of the canvas trough H. Each such stick h is inclosed at its middle by a ring i for strengthening it, and through this ring and the stick h is cut 55 a square hole, through which the end of an arm A or B is passed. This square hole fits the squared part of the arm to be held rigid on its position, while with lifting the stick h as far as head g will allow, the same is free to 60 turn thereon.

The trough H, made of canvas, is of proper shape when stretched between the ends of arms A and B to receive and hold the feed in 65 convenient reach for the horses' mouths.

By raising the lever d to disengage hook e the jaws a will release the wagon-tongue M, and then by pulling out pin c, by pushing the sticks h outward, and by turning them a quarter of a revolution the feed-trough and attachments can be folded to lay flat together and to occupy but a very small space, ready to be 70 reattached to the wagon-tongue at any moment.

What I claim is—

1. The combination, with the feed-trough H, made of canvas and provided with end sticks h, of S-shaped arms A B, for supporting such trough, prong-plates b and pin c, for pivotally connecting arms A B, each arm 80 A B being provided with a segmental jaw-plate a for clamping the same to the wagon-tongue, and a suitable locking device for holding the jaw-plates a in their clamped position, substantially as set forth.

2. The combination, with feed-trough H, made of canvas and provided with end sticks h, and S-shaped arms A B, for supporting such trough, of prong-plates b and pin c, for pivotally connecting arms A B, each arm A B 90 being provided with a segmental jaw-plate a, for clamping the same to the wagon-tongue, and notched lever d, and hook e, for locking such levers in their clamped positions, substantially as set forth.

In testimony whereof I affix my signature in presence of two witnesses.

MICHEL MICHELS.
